(57) **CLAIM**

The ornamental design for a measurement vessel, as shown and described.

DESCRIPTION

FIG. 1 is a perspective view of a measurement vessel showing the new design;
FIG. 2 is another perspective view thereof;

FIG. 3 is an exploded perspective view thereof;

FIG. 4 is a front view thereof;

FIG. 5 is a right side view thereof;

FIG. 6 is a rear view thereof;

FIG. 7 is a left side view thereof;

FIG. 8 is a top plan view thereof;

FIG. 9 is a bottom plan view thereof;

FIG. 10 is a left side view thereof;

FIG. 11 is a cross-sectional view thereof, taken along the line 11-11 in FIG. 10; and,

FIG. 12 is a cross-sectional view of a measurement vessel, taken along the line 12-12 in FIG. 10.

1 Claim, 11 Drawing Sheets
